(54) **THRASHING MACHINE**

(76) Inventor: **Andrew Noble**

Andrew Hobie.
Letters Patent.

The schedule referred to in these Letters Patent and making part of the same, containing a description in the words of the said Andrew Hobie himself of his invention in the Threshing Machine.

The machine frame, without the machinery, is about 10 feet long, 3 feet and about 1/2 inch wide, and 2 feet 4 inches high - supported by four corner posts of hard wood, about 7 inches square, into which are mortised two side and two end pieces of pine timber 2 1/2 inches thick and about fifteen to eighteen inches deep from the toe of the posts; and into these side pieces is framed or mortised a similar end piece, about 1 1/2 inches from the top of the axle, which leaves a space for the rotation of the horizontal cylinder, of which the drain is fixed. On one side is framed into the two end pieces a similar side piece 6 inches within, and parallel to the outer side piece, between which two contiguous side pieces may be twiney wheel or within in the axle of the cylinder, and another wheel on a different axle near the centre of the frame lengthwise.

The cylinder is about 3 feet 3 inches long, being the whole width between the inner and further side pieces lying horizontally and is 3 inches diameter, made of hard wood, but hollow; into the outer surface of which are driven, at regular distances, four, iron (lengthwise of the cylinder at each quarter of its circumference) of iron teeth, quarter of an inch square at the point, and third of

of an inch at the surface of the cylinder, projecting two inches outwards. Under the cylinder one third part of its circumference is a concave fall, made of hard wood commencing about two inches below the axis of the cylinder into which concave fall, concurring to the circle of the cylinder are driven at proper distances four rows of similar iron teeth, the rows also to be lengthwise of the fall, and to project forwards two inches. These iron teeth in the cylinder, will in rotation, draw between the four rows of stationary teeth in the concave fall, leaving the space in front three and one half inches on every side. There-

The tray containing the grain is placed on an intermediate frame made of three pieces, whose upper surface is about one inch and an half above the surface of the cylinder, and is held by bands under the cylinder, these are, rotation and between the iron teeth and the fall or iron teeth the grain is collected and cleanly segregated from the stalks. The stalks and grain in front of the cylinder and fall is passed into a pipe to separate the grain from the straw, and at the farther end of the pipe on the cylinder a fixed set of machinery which set in motion, the ridge and turn the rammers that winnow the grain. The winnowing apparatus may be attached to, and detached from the threshing machine at pleasure. On the upper part of the cylinder is a screen made of bars to collect the stalks in and prevent the straw from passing over the cylinder when in operation.

The cylinder has a wood shaft, into each end of which is driven an iron axle, which extends through the three side pieces of the frame and play

play on composition boxes fixed thereto. On the cylinder axis, between the two contiguous side pieces of the machine frame, is a pulley wheel or whirl, eight inches in diameter and about 6 inches wide, fitting the width between said contiguous side pieces.

At the other end of the frame from the cylinder there is a wood shaft across the three side pieces, being longitudinal at the end on which on the outer side of the frame and on the same side of the pulley wheel or whirl upon the axis of the cylinder, there is fixed the principal perpendicular wheel, viz. ten in diameter, which is turned by hand, having a handle in the form of the wheel, and a crank at the opposite end of the shaft, or to be turned by horse power to move it in adusta.

Between the shaft to the large wheel and the side of the cylinder pulley wheel three fifths of the distance from the former, is a second, iron running, upon composition boxes, which are said to move, the outer and inner side of the frame, on the outer end of which is attached a pulley wheel or whirl 13 inches diameter, over which said wheel stands around the large wheel, and on the same axis between the contiguous sides of the frame is a second wheel, two feet diameter, and about 6 inches wide, over which a road walks around said wheel over the cylinder wheel on the cylinder axis. The three shafts or axes are longitudinally across the top of the frame and all the wheels and whirls stand perpendicular, hence, by turning the large wheel by hand, horse or

or water power, the whole machinery is put in operation and the cylinder by which the grain is threshed, performs nine revolutions to one of the great wheel. The cylinder revolutions can be multiplied in a greater ratio, if required.

The threshing machine, to be turned by hand including the winnowing apparatus, can be furnished to purchasers from \$50 to \$100 dollars and to be run in operation by one horse power, and \$100 additional price. One person can turn it by hand to thresh and winnow thirty bushels of grain in a day, and two hands to turn, and two to attend it can thresh and winnow sixty bushels in a day. The machinery for threshing is a single horse power, consist of an upright shaft with a horizontal wheel on the end connected with the large perpendicular wheel of the machine by bands and pulleys or by some device like friction.

Done at Alfred in the County of York, and State of Maine, this 9th day of November, 1833.

Washington, D. C."*

DEPARTMENT OF THE INTERIOR,

United States Patent Office,

Washington, D. C.,

SIR:

The printed copies of Patent No. *A. N. Nibley*,
1891,
exhausted.

As soon as printed a copy will be mailed you to complete your order.

By direction of the Commissioner:

Very respectfully,

Chief Clerk.
